(57) **CLAIM**

The ornamental design for a personal watercraft water deflector, as shown and described.

DESCRIPTION

FIG. 1 is a top plan view showing a personal watercraft water deflector according to our design;

FIG. 2 is a bottom plan view thereof;

FIG. 3 is a left side elevation view thereof;

FIG. 4 is a right side elevation view thereof;

FIG. 5 is a rear elevation view thereof;

FIG. 6 is a front elevation view thereof; and,

FIG. 7 is a front left perspective view thereof, with a personal watercraft shown in broken lines.

Throughout the Figures, where shown: (i) the broken lines showing additional structure of the personal watercraft water deflector and the personal watercraft on which it is shown are for illustrative purposes only and form no part of the claimed design; and (ii) in FIG. 2, the dotted/dashed lines immediately adjacent shaded surfaces represent unclaimed boundaries of the claimed design. Portions of the personal watercraft water deflector not shown in the Figures and not otherwise described in this Specification do not form part of the claimed design.
